UNITED STATES PATENT OFFICE.

ARNAUD PAUSSER, OF PHILADELPHIA, PENNSYLVANIA.

PROCESS OF AND APPARATUS FOR CURLING HAIR.

1,340,738.

Specification of Letters Patent. Patented May 18, 1920.

Application filed July 20, 1916, Serial No. 110,336. Renewed October 14, 1919. Serial No. 330,669.

To all whom it may concern:

Be it known that I, ARNAUD PAUSSER, a citizen of the Republic of France, (having declared my intention of becoming a citizen of the United States,) and a resident of Philadelphia, Pennsylvania, have invented Improved Processes of and Apparatus for Curling Hair, of which the following is a specification.

10 My invention relates to means for curling or crimping human hair upon the head; and the object of my invention is to provide a device applicable to the head so that living strands of hair may be curled or crimped close against the scalp in a highly efficient and satisfactory manner, and without danger of injury to the individual undergoing such hair curling treatment, and without damage to the hair.

20 As is well known, human hair will soften under the application of hot water, and if the hair is placed in a position to curl or crimp the same when in such softened condition, and held until dry, such curled or crimped effect will be retained for a very great length of time. The important feature of my invention, therefore, is the provision of means whereby the hair or strands of the same may be curled or crimped and subjected to a hot water treatment whereby such strands, or the individual hairs thereof, are softened while in a crimped or curled position and then held until dry in order that they may take a permanent set.

30 35 In addition to providing means for softening the hair, the apparatus which I have devised may be employed to dry the strands of hair in the crimped or curled position after they have been subjected to the softening treatment.

40 These and other features of my invention are more fully described hereinafter, reference being had to the accompanying drawings, in which:

45 45 Figure 1, is an elevation of a complete hair curling apparatus having and containing the features or details constituting the subject of my invention.

50 Fig. 2, is a sectional view of the heating apparatus.

55 Fig. 3, is a perspective view of parts of the structure detached.

Fig. 4, is a perspective view of certain of said parts in a different position.

55 Fig. 5, is a sectional view illustrating a detail of my invention.

Former methods of curling hair upon the head have usually included the use of chemical means for softening the hair. Chemicals, however, have a most injurious effect upon the hair; rendering it brittle and in time causing it to fall out. By the use of the improved process and structure constituting my invention, the hair is treated with hot water and then dried; and no harmful effect results from such treatment.

In the drawings, 1 represents a heating device arranged to receive a strand of hair, which heating device is constructed substantially as follows: A shell 2 is provided made of metal, soft iron for instance, or steel, and having terminals 3 and 4 for electric wire connections 3^a and 4^a from a suitable source of current; such wire connections passing through a controlling switch 5. The shell of this structure is preferably wrapped with a covering 6 of asbestos or similar non-conducting material whereby the operator may be protected from burning on the one hand, or accidental short circuiting of the electrical current on the other hand.

The shell 2 is adapted to receive a rod or stem 7 upon which a strand of hair is wound for curling or crimping; such rod being carried by a pair of rotatively movable disks 8 and 9. These disks are slotted or apertured at 8^a and 9^a, respectively, for the passage of a strand of hair, and such slots, which register, may be provided with end walls 10, which may be struck up from said disks, to grip such strand. A suitable washer 11 is interposed between the disks to prevent leakage.

After the strand of hair has been curled or twisted around the rod 7, the end is tied and then I thoroughly wet the same by a suitable application of water, which may be warm or hot if desired, and to which may be added a small amount of borax, not exceeding 10 per cent. The hair is thoroughly wetted, and after this operation, I wrap the twisted strand in a wet cloth 7^a, preferably one made of wool, which cloth is suitably secured to the rod 7 so that it will be retained around the strand when the shell 2 is set in place.

After this has been done, the shell 2 is placed over the rod 7 carrying the twisted strand, and then an upper pair of disk plates 12 and 13 are placed on the rod and clamped to the shell 2 by a thumb nut 14 engaging

the rod 7. These plates are slotted at 12^a and 13^a for the passage of the end of the strand of hair in case it is long, and they are movable so as to grip the end of the 5 hair if necessary in the same manner as the disks 8 and 9. A washer 15 is preferably interposed between the same to insure a relatively steam tight connection.

The hair and the flannel cloth will carry 10 sufficient water or moisture which, under the influence of heat, will effect a thorough steaming of the hair. This heating action may be continued for a period of twelve to fifteen minutes; at which time substantially 15 all of the moisture originally supplied to the hair and the cloth wrapping will have evaporated. Further evaporation may be effected by opening the slots in the disks forming the cap of the shell, or entirely re- 20 moving the disks, so as to effect a substantial drying of the hair and the cloth inclosing the same, and complete drying may be effected by removing the cloth and leaving the twisted strand in the heating shell. 25 When it is substantially dry, the cloth having previously been removed, the hair may be unwound from the rod 7, and it will be found to possess a permanent twist or curl.

In the operation of my improved process, 30 a suitable protective pad 20 is first placed upon the head; such pad having an aperture 21 through which a strand of hair is passed. This strand is then passed through the registering apertures of the disks 8 and 35 9, referred to, and by imparting rotative movement to said disks with respect to each other, the apertures in the same are substantially closed; bringing their end walls against the strands of hair so as to insure a 40 substantially steam-tight joint. The lower disk is provided with a threaded stem 8^b adapted to receive the rod 7 around which the hair is wound, and when this rod is set in place, it clamps the gasket 11 disposed 45 between the disks tightly against the roots of the hairs constituting the strand.

Then the hair is wound around the stem, tied in place, wetted, and the woolen cloth, also thoroughly wet, is tightly wrapped or 50 wound around the strand of hair. Then the shell is placed over the covered strand, after which the disks 12 and 13 forming the cap for the shell 2 are set in place; the same passing over the rod upon which the hair is 55 wound, and the hair passing out through the registering apertures in said disks, if it is long enough. These disks are clamped to the shell by the means described, and the current is then turned on, heating the wet 60 hair and the cloth around the same.

The heat is raised to a substantial boiling temperature for ten or fifteen minutes, thereby softening the hair so that it can take 65 the set desired. At the end of the desired heating operation, the upper cap or closure

may be opened or removed, and the hair allowed to dry while still wound on the rod. This drying may be without heat, or it may be assisted by heat developed within the shell electrically.

By preference, the rods 7 employed, are 70 of the shape shown in Fig. 5; being smaller at the lower portion of the same so that the hair, which is thicker at the roots, can be more readily accommodated.

In the use of my invention, it is necessary 75 to employ a plurality of the heating shells, since a complete operation of curling the hair on the head may include the crimping or curling of twenty-five or thirty strands 80 on the head. It is desirable, further, to support the heating shells in a substantially vertical position, hence I provide a device whereby these structures may be suspended 85 from the ceiling, or a suitable point adjacent the ceiling, and provided with counterweights so that the heating shells will be properly balanced and will not weigh down the head to which they are applied.

This suspending structure may comprise a 90 canopy 25, having a plurality of pulleys 26 from which the heating devices 1 may be suspended, and for this purpose the electric cord may be employed, carrying a counterweight 27. The canopy also may have a 95 central rod or tube 28, in which may be telescopically fitted an extension rod 29, and the latter may carry angular extension rods 30, (only one of which is shown) to which adjustable connections 31 may be secured; the 100 same carrying chucks 32 which may be employed to support the rods 7 while the hair is being wound thereon, each of such rods carrying a pad 20 and the disks 8 and 9 through which the strand of hair is passed. 105 The chucks may be disposed at any desired angle to properly receive the strands of hair and their use leaves both hands of the operator free to twist or wrap the hair around the rods 7. Furthermore by adjustably suspending the heating structures from suitable counterbalancing devices supported 110 near the ceiling, both hands of the operator are free to make any desired changes, or any repositioning of such heating devices with 115 respect to the strands of hair. It will be understood, of course, that a number of the heating devices will be in use at the same time; all of which will be supported by independent counterbalancing means.

It will be understood, of course, that in 120 some instances I may fill the heating shell with water and practically boil the hair in the same. Such water may, if desired, have a small proportion of borax added to it. In 125 such instance, the shell may be threaded onto the lower disk structure to insure a water-tight connection.

In the operation of my improved process with the structure described and illustrated,

it is unnecessary to employ anything that will have an injurious effect upon the hair; the whole process of crimping or curling the hair consisting simply in softening it by the

5 application of hot water while wound in a curled or crimped condition upon a suitable rod, the hair being subsequently dried while still wound upon such rod so as to permanently retain the curled condition.

10 I claim:

1. In apparatus for curling hair, the combination of a shell, means for disposing a strand of crimped or curled hair within the same, means for sealing the ends of said shell to render the same leak-proof, means for applying moisture to said strand, and means for heating said moisture while said strand is in the crimped or curled position within the sealed shell.

20 2. In apparatus for curling hair, the combination of a shell, a rod within the same upon which a strand of hair may be wound, means for confining the strand of hair to the rod, means for sealing the ends of said shell to render the same leak-proof, means for applying moisture directly to said strand, and means for heating said moisture while said strand is in the crimped or curled position within the sealed shell.

30 3. In apparatus for curling hair, the combination of a metal shell, means for disposing a strand of crimped or curled hair within the same, means for sealing the ends of said shell to render the same leak-proof, means for applying moisture to said strand, and electrical means for heating said moisture while said strand is in the crimped or curled position within the sealed shell, said shell having terminals for utilizing an electric current as the heating means.

40 4. In apparatus for curling hair, the combination of a metal shell, a tapered rod within the same upon which a strand of hair may be wound in a crimped or curled condition, means for sealing the ends of said shell to render the same leak-proof, means for applying moisture to said shell, and electrical means for heating said moisture while said strand is in the crimped or curled position within the sealed shell, said shell having terminals for utilizing an electric current as the heating means.

50 5. The combination, in a hair curling device, of a closed moisture retaining shell, means for heating such moisture, means for disposing a strand of hair within said shell in a twisted condition, and means for sealing the ends of the shell to render the same leak-proof; such sealing means gripping the strand of hair at each end of the shell and forming therewith a moisture-tight joint.

60 6. The combination, in a hair curling device, of a moisture retaining shell, means for heating such moisture, means for disposing a strand of hair within said shell

in a twisted condition, covering means for closing each end of said shell against leakage, and means carried by the covers for gripping the strand of hair to prevent leakage of the heated moisture.

70

7. A hair curling device comprising a moisture retaining shell, moisture-tight closures at the ends of the same, a tapered rod secured within said shell and around which a strand of hair may be wound, and means for heating the moisture within said shell.

8. A hair curling device comprising a moisture retaining shell, a rod therein around which a strand of hair is wound, covers for closing the ends of said shell, means for clamping said covers to the ends of said rod to render the shell leak-proof, and means for heating the moisture within said shell.

85 9. The combination, in a hair curling device, of a shell, a plurality of disk-like members having registering apertures disposed at one end of said shell, said registering apertures being adapted for the passage of a strand of hair, means for locking said disks in such position as to grip the strand and form a moisture-tight joint adjacent the roots of said strand of hair, a rod carried by said disk-like member and substantially centrally disposed with respect to the shell 90 upon which said strand of hair may be wound, means for applying moisture to the hair, a cap or closure secured to the upper end of said shell through which said rod passes, and means for heating the moisture 100 within the shell.

10. The combination, in a hair curling device, of a shell, a plurality of disk-like members movable with respect to each other and having registering apertures disposed at each end of said shell, said members serving to render the latter leak-proof, said registering apertures being adapted for the passage of a strand of hair, means for locking each set of said disks in such position as 110 to grip the strand and form a moisture-tight joint adjacent the roots of said strand of hair, a rod connected to said sets of disk-like members and substantially centrally disposed with respect to the shell upon 115 which the strand of hair may be wound, said rod passing through the disk-like members of the upper end of the shell, means for applying and maintaining moisture directly adjacent said strand of hair, and means for 120 heating the moisture within the shell.

11. The combination, in a hair curling device, of a shell, disk-like members having registering apertures disposed at one end of said shell, said registering apertures being 125 adapted for the passage of a strand of hair, means for locking said disks in such position as to grip the strand and form a moisture-tight joint adjacent the roots of the strand of hair, a rod carried by said shell upon 130

which the strand of hair may be wound, means for closing the upper end of said shell, means for heating the moisture within the shell, and means for supporting said structure above the head whereby strain upon the strand of hair is relieved.

12. The combination, in a hair curling device, of a closed moisture retaining shell, means for heating such moisture, means for disposing a strand of hair within said shell, means for closing each end of said shell against leakage, said means serving also for gripping the strand of hair at each end of the shell, and means for supporting said structure above the head whereby strain upon the strand of hair is relieved.

13. In apparatus for curling hair, the combination of a closed moisture-retaining shell, means for disposing a strand of crimped or curled hair within the same, means for applying moisture to said strand, means for heating said moisture while said strand is in the crimped or curled position, and means for protecting the head and scalp of the person operated upon.

14. In apparatus for curling hair, the combination of a closed moisture-retaining shell, means for disposing a strand of crimped or curled hair within the same, means for applying moisture to said strand, means for heating said moisture while said strand is in the crimped or curled position, and a protective pad interposed between the shell and the head of the person operated upon.

15. In apparatus for curling hair, the combination with a closed metal shell having means for disposing a strand of crimped or curled hair within the same, means for applying moisture to said strand, means for sealing each end of the shell to render the same leak-proof, and means for heating said

moisture while said strand is in the crimped or curled position, of a support for said shell and counterbalancing means for maintaining the shell in proper position with respect to the head of the person operated upon.

16. In apparatus for curling hair, the combination of a shell, means for disposing a strand of crimped or curled hair within the same, means for sealing the ends of said shell around the strand of hair, a porous moisture-carrying wrapping for applying moisture to said hair, and means for heating said moisture while said strand is in the crimped or curled position.

17. The combination, in a hair curling device, of a moisture retaining shell, means for disposing a strand of hair within said shell in a twisted condition, means for sealing the ends of said shell around the strand of hair, a moisture containing cloth wrapped around said twisted hair, means for holding the moisture in said shell against leakage, and means for heating said moisture.

18. The process of curling hair on the head of the wearer, which consists in twisting or crimping a strand of the hair, applying moisture to such strand, confining the moisture to the strand within a closed container, and simultaneously heating the same.

19. The process of curling hair on the head of the wearer, which consists in disposing a strand of hair in a twisted or crimped condition, applying moisture to such strand, confining such moisture to the strand within a closed container, simultaneously heating the moisture to substantial evaporation, and subsequently drying the strand of hair while maintaining the same in the twisted or crimped condition.

ARNAUD PAUSSER.
